UNITED STATES PATENT OFFICE

GUSTAVE B. JENSEN, OF NEW YORK, N. Y., ASSIGNOR TO PASS & SEYMOUR, INC., OF SYRACUSE, NEW YORK, A CORPORATION OF NEW YORK

DESIGN FOR A LIGHTING FIXTURE OF THE WALL BRACKET TYPE

Application filed November 18, 1930. Serial No. 37,697. Term of patent 7 years.

To all whom it may concern:

Be it known that I, GUSTAVE B. JENSEN, a citizen of Denmark and resident of the city, county, and State of New York, have invented a new, original, and ornamental Design for a Lighting Fixture of the Wall Bracket Type, of which the following is a specification, reference being had to the accompanying drawings, forming a part thereof, and in which:

Figure 1 is an elevation of a lighting fixture of the wall bracket type incorporating the design of the present invention;

Figure 2 is an edge view thereof; and

Figure 3 is a plan view thereof.

The dotted lines in the figures represent a tubular form of lamp of the incandescent

type intended for use with the bracket as shown.

The lighting fixture comprises a substantially flat rectangular base having diagonally opposite reentrant corners. This base supports at each end a tubular member which receives the lamp. Each tubular member is circumferentially fluted and at one side abuts the reentrant edge. The flutes are carried out only to the edge of the opposite side of the base. The whole intermediate portion of the base is plain.

I claim:

The ornamental design for a lighting fixture of the wall bracket type substantially as shown and described.

GUSTAVE B. JENSEN.
